ANTIAIRCRAFT PROJECTILE

Walter B. Fraser, St. Augustine, Fla.

Application June 17, 1942, Serial No. 447,413

6 Claims. (Cl. 102—63)

This invention relates to certain new and useful improvements in anti-aircraft projectiles.

The primary object of the invention is to provide an anti-aircraft projectile wherein the shell projected from the cartridge during firing carries a spooled cable with a parachute at one end of the cable and a weighted member at the other end of the cable, with timed fuse and firing devices for discharging the cable, parachute and weight from the projectile with the suspended end projected in the path of flight of an enemy plane for the purpose of fouling the airplane propellers, ailerons and other control elements of an enemy airplane, it being understood that a plurality of such projectiles will be substantially simultaneously fired into the path of an enemy airplane in flight.

A further object of the invention is to provide an anti-aircraft projectile of the foregoing character wherein the shell of the projectile houses a canister and within which canister there is housed a coiled cable carrying a parachute at one end with the other end of the cable secured to a bottom closure wall for the canister, selectively timed firing devices within the nose of the projectile and base of the canister for the discharge of the canister from the projectile casing and the subsequent displacement of the bottom closure wall for the canister, with the unwinding and extension of the cable and parachute from the canister for placement in the path of flight of an enemy airplane.

With the above and other objects in view that will become apparent as the nature of the invention is better understood, the same consists in the novel form, combination and arrangement of parts hereinafter more fully described, shown in the accompanying drawings and claimed.

In the accompanying drawings:

Fig. 1 is a fragmentary longitudinal sectional view of an anti-aircraft projectile constructed in accordance with the present invention, the canister therein containing a parachute and suspension cable being shown in elevation.

Fig. 2 is a longitudinal sectional view of the canister containing the parachute and cable removed from the projectile casing and showing the center cord tube for housing the parachute and the coiled cable disposed between the cord tube and wall of the projectile casing.

Fig. 3 is a side elevational view of the canister removed from the projectile casing and with the weighted bottom wall of the canister to which one end of the cable is attached displaced relative to the canister.

Fig. 4 is a side elevational view of the parachute and cable in its suspended or floating position, with the weighted bottom wall of the canister at the lower end of the cable,

5 Fig. 5 is a fragmentary cross-sectional view taken on line 5—5 of Fig. 2,

Fig. 6 is an inner face view of the weighted bottom wall of the canister,

10 Fig. 7 is a detail sectional view taken on line 7—7 of Fig. 3, and

Fig. 8 is a fragmentary longitudinal sectional view taken on line 8—8 of Fig. 2.

15 Referring more in detail to the accompanying drawings and particularly to Fig. 1, there is fragmentarily illustrated an anti-aircraft projectile comprising a shell 10 having the usual powder or other explosive charge 11 therein and in the forward end of which shell there is mounted a projectile casing 12 carrying a soft metal rifling band 13 and a solid projectile nose 14.

20 The present invention primarily relating to the idea of projecting floating cables in the path of flight of enemy airplanes for the purpose of fouling the propellers of such planes or other flying control elements thereof, the projectile casing 12 houses a cylindrical container or canister 15 that when housed within the projectile casing 12 terminates in spaced relation to the forward end of the chamber in said casing to provide a compartment for a powder charge 16.

25 The rear end of the canister 15 is closed by a weighted end wall 17 carrying an annular base flange 18 that is flush with the inner end of the projectile casing 12 as shown in Fig. 1, the diameter of the canister 15 being such as to provide limited frictional contact with the inner face of the projectile casing 12. To retain the end wall 17 seated within the inner end of the canister 15, there is provided an annular band 19

30 that is welded or otherwise secured to the inner face of the end wall 17 and is of such diameter as to snugly fit within the adjacent end of the canister and to be spot-welded or otherwise secured to said canister as at 20. A funnel-shaped wall 21 is secured at its outer edge to the forward end of the ring 19 and the inner end thereof has a packing joint connection with the annular groove 22 concentric of the end wall 17 and provides a powder receiving chamber 23 between said funnel-shaped wall 21, ring 19, and end wall 17.

35 The forward end of the canister is closed by a concaved end wall 24. As shown more clearly in Figs. 2, 5, 7 and 8, the canister 15 is provided with an axially positioned tubular core 25 with the rear end thereof

40 45 50 55 60 65 70 75 80 85 90 95

abutting the adjacent face of the weighted inner end wall 17, while the forward end of the tubular core 25 is flanged outwardly as at 26 for spot-welding or securing engagement with a cross wall 27 in the canister adjacent the concaved end wall 24. The cylindrical cannister 15 and the axially positioned tubular core 25 provide inner and outer concentric chambers 28 and 29, the core chamber 28 housing a parachute 30 while the canister chamber 29 houses a spirally wound cable 31. As shown in Figs. 2 and 5, the tubular core 25 has one side thereof longitudinally pressed inwardly as at 32 to provide a longitudinally extending surface groove for the reception and passage of the strand section 31^a of the cable, the inner face of the weighted end wall 17 within the annular groove 22 having an arcuate recess 33 therein to permit passage of the strand section 31^a of the cable and entry into the core chamber 28 for attachment to the cords 34 of the parachute 30. The cable strand 31 at the forward end of the tubular core 25 is directed outwardly and laterally as at 31^b with such portion of the strand overlying a radial slot 35 in the cross plate 27 and then forming a part of the coiled cable 31. The end of the coiled cable 31 within the canister chamber 29 extends into an opening 36 formed in the weighted end wall 17 with the terminal end thereof split and welded as at 36 to the end wall 17 while the cross screw 37 threaded into the cross opening 38 in the end wall engages the adjacent end of the cable for further anchoring the same to the end wall.

The projectile has been designed to be fired from standard anti-aircraft guns, and time fuses are associated with the powder chamber 16 in the nose of the projectile and the powder chamber 23 at the base of the canister for the sequential discharge of the canister from the projectile casing and the displacement of the weighted end wall 17 of the canister for the discharge of the cable and parachute. A fuse line 39 extends longitudinally of the tubular core 25, one end 39^a thereof being extended through an angular opening in the weighted end wall 17 for communication with the powder chamber 23 while the forward end of the fuse line 39 as shown at 39^b in Fig. 2 extends into the powder chamber 16. The powder chamber 16 is first operated for the removal of the canister 15 from the projectile casing 12 and the powder chamber 23 is next operated to displace the weighted end wall 17 of the canister as shown in Fig. 3, the weight of the end wall 17 unwinding the cable 31 from the chamber 29 and finally removing the parachute 30 from the cord chamber 28 with the cable, parachute and end wall assuming the floating or suspended position illustrated in Fig. 4. If desired, the powder chamber 16 may be eliminated and with the canister 15 remaining in the projectile, the end wall 17 of the canister may be displaced for the removal of the cable and parachute from the canister.

From the above detailed description of the invention, it is believed that the construction and operation thereof will at once be apparent, and while there is herein shown and described the preferred embodiment of the invention, it is nevertheless to be understood that minor changes may be made therein without departing from the spirit and scope of the invention as claimed.

I claim:

1. In an anti-aircraft projectile of the character described, a projectile casing, a canister therein, explosive means for ejecting the canister from the projectile casing, a weighted end wall for the canister, a parachute and cable in the canister with one end of the cable attached to the parachute and the other end of the cable attached to the end wall, a partition in the canister adjacent to and cooperating with the weighted end wall to form a powder blast chamber, and a time fuse associated with the powder blast chamber for the operation thereof to displace the end wall for the release of the parachute and cable with the parachute and weighted end wall operative for holding the cable perpendicularly suspended.
2. In an anti-aircraft projectile of the character described, a projectile casing, a canister therein, a weighted end wall for the canister, a parachute and cable in the canister with one end of the cable attached to the parachute and the other end of the cable attached to the end wall, a partition in the canister adjacent to and cooperating with the weighted end wall to form a powder blast chamber, and a time fuse associated with the powder blast chamber for the operation thereof to displace the end wall for the release of the parachute and cable with the parachute and weighted end wall operative for holding the cable perpendicularly suspended, the end of the canister adjacent the nose of the projectile terminating in spaced relation to said nose to provide a powder blast chamber with which said time fuse is associated for discharging the canister from the projectile prior to operation of the first-named powder blast chamber.
3. In an anti-aircraft projectile of the character described, a projectile casing, a canister therein, explosive means for ejecting the canister from the projectile casing, a weighted end wall for the canister, a parachute and cable in the canister with one end of the cable attached to the parachute and the other end of the cable attached to the end wall, a partition in the canister adjacent to and cooperating with the weighted end wall to form a powder blast chamber, and a time fuse associated with the powder blast chamber for the operation thereof to displace the end wall for the release of the parachute and cable with the parachute and weighted end wall operative for holding the cable perpendicularly suspended, the end of the canister adjacent the nose of the projectile terminating in spaced relation to said nose to provide a powder blast chamber with which said time fuse is associated for discharging the canister from the projectile prior to operation of the first-named powder blast chamber.
4. In an anti-aircraft projectile of the character described, a projectile casing, a canister therein, a weighted end wall for the canister, a parachute and cable in the canister with one end of the cable attached to the parachute and the other end of the cable attached to the end wall, a partition in the canister adjacent to and cooperating with the weighted end wall to form a powder blast chamber, and a time fuse associated with the powder blast chamber for the operation thereof to displace the end wall for the release of the parachute and cable with the parachute and weighted end wall operative for holding the cable perpendicularly suspended, the end of the canister adjacent the nose of the projectile terminating in spaced relation to said nose to provide a powder blast chamber with which said time fuse is associated for discharging the canister from the projectile prior to operation of the first-named powder blast chamber, a tubular core in the canister with the parachute nor-

mally confined therein while the cable is coiled around the tubular core.

5. In an anti-aircraft projectile of the character described, a projectile casing, a canister therein, explosive means for ejecting the canister from the projectile casing, a weighted end wall for the canister, a parachute and cable in the canister with one end of the cable attached to the parachute and the other end of the cable attached to the end wall, a partition in the canister adjacent to and cooperating with the weighted end wall to form a powder blast chamber, and a time fuse associated with the powder blast chamber for the operation thereof to displace the end wall for the release of the parachute and cable with the parachute and weighted end wall operative for holding the cable perpendicularly suspended, a tubular core in the canister with the parachute normally confined therein while the cable is coiled around the tubular core, the tubular core being longitudinally indented to provide an external groove therein with the end of the cable attached to the parachute extending from the weighted end of the canister through said groove for coiling around said core while the other end of the cable attached to the weighted end wall assures immediate unwinding of the cable upon displacement of the weighted end wall.

6. In an anti-aircraft projectile of the character described, a projectile casing, a canister

therein, a weighted end wall for the canister, a parachute and cable in the canister with one end of the cable attached to the parachute and the other end of the cable attached to the end wall, a partition in the canister adjacent to and cooperating with the weighted end wall to form a powder blast chamber, and a time fuse associated with the powder blast chamber for the operation thereof to displace the end wall for the release of the parachute and cable with the parachute and weighted end wall operative for holding the cable perpendicularly suspended, the end of the canister adjacent the nose of the projectile terminating in spaced relation to said nose to provide a powder blast chamber with which said time fuse is associated for discharging the canister from the projectile prior to operation of the first-named powder blast chamber, a tubular core in the canister with the parachute normally confined therein while the cable is coiled around the tubular core, the tubular core being longitudinally indented to provide an external groove therein with the end of the cable attached to the parachute extending from the weighted end of the canister through said groove for coiling around said core while the other end of the cable attached to the weighted end wall assures immediate unwinding of the cable upon displacement of the weighted end wall.
